CLAIM

The ornamental design for a package, as shown and described.

DESCRIPTION

FIG. 1 is a top, front perspective view of a first embodiment of a package showing my new design in a closed position.

FIG. 2 is a top, front perspective view thereof, in an open position.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a top plan view thereof, the bottom being a mirror image thereof; and,

FIG. 8 is a top, front perspective view of a second embodiment showing a further embodiment thereof in an open position, the remaining views being identical to FIGS. 1, and 3 through 7.
